UNITED STATES PATENT OFFICE

2,638,102

HAIR-NET OR THE LIKE AND METHOD OF
MAKING SAME

Henry F. Goldsmith, Philadelphia, Pa.

Application July 19, 1948, Serial No. 39,403

5. Claims. (Cl. 132—49)

1

The present invention relates to hair-nets, and it relates more particularly to hair-nets of the type wherein a generally rectangular length of open-mesh fabric is gathered along two parallel sides and tied to form a generally concave structure having a mouth or opening defined by the other two sides.

An object of the present invention is to provide a new and improved construction for hair-nets. Another object of the present invention is to provide a hair-net construction which is simple, inexpensive and durable, and which provides neat appearance and comfort. Still another object of the present invention is to provide a construction of the general type referred to hereinabove, which is particularly well adapted for use with fabrics woven or knitted from threads of synthetic plastic material, such as nylon, or the like.

Other objects and advantages in the construction of the present invention are apparent in the following detailed description, appended claims and accompanying drawings.

It has been suggested in the past to construct hair-nets of open-mesh fabric, woven or knitted in any one of various different ways known in the art to provide a plurality of generally diamond-shaped openings. As disclosed in my Patent 2,104,538, each hair-net may be formed from a generally rectangular strip of open-mesh material having a pair of parallel cut edges (the individual pieces being cut from a length of material as it comes from the knitting machine or lace machine or the like), and a pair of parallel bound or selvage edges (which usually incorporate elastic threads to permit them to be stretched); the cut edges being Shirred or gathered and fastened to provide a generally concave structure having a mouth or opening by the selvage edges.

It has been conventional, heretofore, to fasten the gathered cut edges by stitching across the gathered portions, as disclosed in my Patent 2,104,538 or by tying a thread tightly around each of the shirred or gathered ends or by knotting the gathered ends, or by otherwise mechanically fastening them to prevent them from coming apart when the mouth of the hair-net is spread apart during use.

While these conventional fastening means have been acceptable with hair-nets constructed of natural fibers, they have proven unsatisfactory with hair-nets constructed of nylon or other synthetic plastic threads which have an extremely smooth finish offering very slight fric-

2

tional resistance so that they pull out easily from the stitched or tied or knotted constructions.

The present invention contemplates a new and improved hair-net construction intended particularly for use with synthetic plastic materials and providing a positive and secure fastening structure for the cut edges of the hair-net.

Generally speaking, the present invention comprehends a hair-net of the type disclosed hereinabove, constructed at least in part of threads of synthetic plastic material wherein the gathered cut edges are generally permanently and inseparably connected by tightly encircling sleeves or clips or tubes of synthetic plastic material fused or bonded to at least some of the plastic threads of the hair-net so as to provide more-or-less integral construction capable of resisting all normal stresses during use.

For the purpose of illustrating the invention, there are shown in the accompanying drawings forms thereof which are at present preferred, although it is to be understood that the various instrumentalities of which the invention consists can be variously arranged and organized and that the invention is not limited to the precise arrangements and organizations of the instrumentalities as herein shown and described.

Referring to the accompanying drawings in which like reference characters indicate like parts throughout:

Figure 1 represents a perspective view of one embodiment of the present invention as it appears in use.

Figure 2 represents a fragmentary plan view of a length of open-mesh or netted synthetic plastic material from which a number of hair-nets can be formed.

Figure 3 represents a more or less schematic elevational view, on a somewhat reduced scale, showing the manner in which fastening clips are applied to the length of material of Figure 2 and the length is cut into individual hair-nets.

Figure 4 represents a plan view, on generally the same scale as Figure 2, showing the appearance of an individual hair-net after it has been cut from the elongated strip of Figure 3; the selvage edges being shown as spread apart.

Figure 5 represents a fragmentary elevational view, on an enlarged scale, showing the appearance of one of the ends of the hair-net of Figure 4.

Figure 6 represents a cross-sectional view, on a greatly enlarged scale, generally along the line 6—6 of Figure 5.

Figure 7 represents an elevational view, gener-

ally on the same scale as Figure 5, showing the fastening clip 15 as it would appear in opened or rolled-out position.

Figure 8 represents a perspective view of a machine which may be used in applying the fastening clips to the strip of open-mesh material.

Figure 9 represents a fragmentary side elevational view of the embodiment of Figure 8.

Figure 10 shows the machine of Figure 9 in a different phase of operation.

In one embodiment of the present invention shown generally in Figures 1 and 4, I may provide a hair-net formed of threads of flexible synthetic plastic material, such as nylon or the like, having an open-mesh structure formed by intersecting chains 10 of any conventional woven or knitted construction forming a generally diamond-shaped pattern.

The open-mesh fabric may be formed on a double-needle bar warp-type knitting machine having two independently-operable guide-bars as described in my Patent 2,104,538.

However, it is to be understood that the present invention is not limited to the details of construction of the open-mesh material and can be used with all types of open-mesh material including materials otherwise knitted or woven, including material constructed on lace-making machines. Similarly, the fabric may have a hexagonal or other pattern in place of the diamond-shaped pattern shown in the drawing.

The individual hair-nets are formed from an elongated length 11 of the open-mesh material, shown fragmentarily in Figure 2, having parallel selavage edges 12 and 13.

The selavage edges are formed with elastic threads or strands (preferably consisting of an inner core of synthetic or natural rubber around which a textile thread of the same color as the hair-net is wound) over which the terminal loops of the chain 10 are passed.

In the formation of individual hair-nets from the length 11, shown in Figure 2, the length is first stretched in a manner shown in Figure 3 (wherein the rubber strands in the selavage edges 12 and 13 are extended to somewhat more than twice their normal constricted length) to form the length of material into what resembles a bulky cord or rope.

At predetermined intervals (corresponding to the lengths required for the individual nets) along the so-stretched length 11, pairs of synthetic plastic sleeves or tubular clips 15 are applied and fused, in a manner to be more fully described hereinbelow, so as to provide a small intervening portion or puff 16 therebetween.

As the final step in the construction of the individual hair-nets, each intervening portion or puff 16 is cut generally along the lines 17 as shown in Figure 3, to provide each hair-net with a pair of small tassels 18 extending beyond each of the clips 15 as indicated particularly in Figures 4 and 5.

While, in Figure 3, the length of open-mesh material is shown as having a number of pairs of fastening sleeves or clips applied thereto, I prefer to apply one pair of clips at a time and thereafter to cut the intervening puff 16 (along lines 17-17) before applying the next pair of sleeves or clips, in which case there is never any actual structure corresponding to the schematic showing of Figure 3 (wherein a plurality of pairs of fastening sleeves or clips are applied to an uncut length of open-mesh fabric).

However, it is to be understood that the process of the present invention also contemplates the affixation of a plurality of pairs of fastening sleeves or clips prior to the cutting of the length of open-mesh fabric into individual hair-nets or the like.

In Figures 8 and 9, there is shown, more or less schematically, a machine which may be employed in affixing the fastening tubes or clips to the strip of netted material and in thereafter cutting the strip as steps in the manufacture of the hair-nets of the present invention.

Thus, the machine includes a frame indicated generally by the reference character 19 having an integrally-formed base 20 which may be bolted or otherwise securely affixed to a supporting table 21.

The frame 19 is generally forwardly and downwardly tilted as shown particularly in Figures 9 and 10 and is provided with a shoulder 22 which slidably supports a female die-member 23 to be hereinafter more fully described.

A guide-rod 24 is fastened to the front end of the die-member 23 and extends through an opening 25 formed in the front end of the frame 19. A helical spring 26 is mounted on the guide-rod 24 and normally tensions the female die-member 23 to the uppermost position shown in solid lines in Figure 9.

The die-member 23 includes a generally J-shaped die 27 of metal or other heat-conducting material having an elongated lower arm 28, a rounded bottom 29 and a relatively short upper arm 30 having an uppermost beveled free edge or shear-lip 31.

A slot 32 extends generally centrally of the bottom 29 and the arm 30, terminating at about approximately half-way up said arm 30.

A fixed cutting blade 33 is mounted upon the frame 19 so that its tapered cutting-edge 34 extends into the slot 32.

The die-member 23 is provided with internal electrical heating coils 35 whereby the J-shaped die 27 is maintained at elevated temperature.

A male die-member 36 is bolted or otherwise rigidly fastened to the lower end of a shaft 37 which is slidably carried by an apertured collar 38 formed at the upper end of the frame 19. The male die-member 36 is so dimensioned that it can move intermediate the arms 28 and 30 of the female die 27 in snug sliding relationship thereto. The lowermost free edge of the male die-member 36 is made concave as at 54 to provide an upper transversely-extending shear-lip 55 which contacts with the shear-lip 31 of the arm 30 to give a cutting action as will be described hereinbelow.

A slot 56 extends upward from the edge 54 generally centrally of said die-member 36 and in alignment with the slot 32 and the cutting-blade 33. The upper end of the slot 56 is formed as a rounded enlarged portion 57 whose function will be hereinafter described.

The upper end of the shaft 37 carries a curved shoe or cam-follower 39.

A helical spring 40 is mounted on the shaft 37 so that it seats against the collar 38 and bears against the underside of the cam-follower 39 thereby tensioning the shaft 37 upwardly so as to maintain the cam-follower 39 in contact with a cam 41 which is adapted to be turned by a shaft 42 from any appropriate driving means (not shown).

It is apparent that rotation of the cam 41 will cause reciprocation of the shaft 37 and the male die-member 36.

Elongated strips 43 of flexible synthetic plas-

tic material, such as acetate Celluloid or the like, are wound on a pair of spools 44 rotatably mounted on a shaft 45.

The strips 43 extend downward from the spools 44 and pass over grooves 46 formed in a power-roll 47 mounted on a shaft 48.

A pair of idler-rolls 49 carried by a shaft 50 are adapted to extend within the grooves 46 and to bear against the strips 43 so as to provide the necessary friction to permit the power-roll 47 to move said strips 43.

The strips 43 extend downward from the rolls 47 and 49 and through a pay-out member 51 which is mounted on a shaft 52 so that its lower-most nose or pay-out tip 53 is somewhat above the free edge 31 of the upper arm 30. The pay-out member 51 is preferably of generally two-piece construction including matching top and bottom sections 58 and 59 which are connected by a plurality of bolts 60. Sufficient clearance is provided intermediate the sections 58 and 59 as to permit the strips 43 to pass freely therebetween (under the action of the rolls 47 and 49). This clearance may be provided by forming matched grooves (not shown) on the adjoining faces of the sections 58 and 59. Instead, the bolts 60 can be so constructed as to space the two sections apart sufficiently to provide the necessary clearance.

A basin 61 is supported by the front end of the frame 19 by means of an extension arm 62. A sponge or other similar porous pad 63 is positioned within the basin 61 and an appropriate solvent for the synthetic plastic is fed thereto from a reservoir 64 through a delivery tube 65. Where the synthetic plastic employed is acetate Celluloid, a mixture of acetone and ethanol, preferably in generally equal parts (measured either by weight or by volume inasmuch as they both have a specific gravity of approximately 0.79) may be used. This solvent is also effective with various other synthetic plastics.

However, other solvents and solvent-mixtures may be employed and the present invention is not limited to this particular composition.

A restraining member 66 which is generally ladder-shaped is positioned to one side of the table 21 while a pronged holding member 67 is bolted or otherwise securely fastened to the opposite edge of the table 21 with its prongs disposed slightly above the level of the basin 61. The length 11 of netted open-mesh material is passed from a storage container 68 upward and is interlaced between the rungs of the ladder-shaped restraining member 66 from which it is brought generally horizontally across to the pronged holding member 67 onto which its free end is placed, so that the strip extends in generally taut condition, slightly above the level of the basin 61 and somewhat to the rear of the basin but in front of the female die-member 23 as indicated in Figure 8. The interlacing of the length 11 with the rungs of the ladder-shaped restraining member 66 provides sufficient friction to keep the horizontal straight-line portion 11-a of the length 11 generally taut without excessive slackening or sagging.

The process for applying the individual sleeves or clips 15 to the length 11 of netted open-mesh material is generally as follows.

The length 11 of material is placed within the container 68 and one of its free ends is brought upward and laced through the ladder-shaped member 66 and is then brought horizontally across as at 11-a and hooked on to the

pronged holding-member 67 so that the horizontal portion 11-a is in generally taut position as described above. The center part of the portion 11-a is then grasped by the operator and brought down to the position shown in dash-dot lines at 11-b in Figure 8 wherein it contacts the pad 63. The length of material is then rubbed and rolled back and forth upon the pad 63 so that it is wet by the solvent.

Thereafter, the moistened or wetted portion of the length of material is moved by the operator and passed across the upper arm 30 of the J-shaped die 27 and positioned adjacent the rounded bottom 29 as indicated at 11-c in dash-dot lines in Figure 8.

As the moistened length of material is passed across the free edge 31 of the upper arm 30, it wipes against the strips 43 (protruding downward from the nose 53 of the pay-out member 51) and transfers some of the solvent to the strips 43.

With the length 11 thus in position within the J-shaped die 27, the operator presses any appropriate foot-pedal (not shown) so as to cause the shaft 42 and the cam 41 to rotate. Rotation of the cam 41 causes the shaft 37 and the male die-member 36 to be moved downward from the uppermost position shown in solid lines in Figure 9 to the intermediate position shown in dash-dot lines in Figure 9.

The shaft 48 and the power-roll 47 are synchronized with the shaft 42 so that, during this preliminary movement of the male die-member 36, the strips 43 of plastic are payed out from the position shown in solid lines in Figure 9 to the position shown in dash-dot lines in Figure 9 (wherein they extend downward along the arm 28 of the die 27 and into contact with the length 11).

Further rotation of the shaft 42 and the cam 41 causes the male die-member 36 to move further downward, the strips of plastic 43 being cut by the shear-lip 55 in cooperation with the shear-lip 31. As the male die-member 36 continues to move downward, it rolls the severed ends of the strips 43 around the length 11, tightly compressing the intervening open-mesh material in the process, after which the concave edge 54 contacts the strip 11 and forces the female die-member 23 downward against the pressure of its spring 26, to the lowermost position shown in Figure 10.

This downward movement of the male die-member 36 and the female die-member 23 forces the length of material 11 against the cutting edge 34 of the cutting-blade 33 thereby severing the intervening portion 16 along the lines 17-17 of Figure 3 (the cutting-blade 33 being positioned within the slots 32 and 56 in the lowermost position of the two die-members).

That part of the portion 16 intervening the rolled up sleeves 15 of synthetic plastic, which is severed by the side edges of the cutting-edge 34 (cooperating with the slotted edge 54 of the male die-member 36) enters the enlarged upper end of the slot 56 and falls clear of the male die-member 36 on the return stroke thereof.

The length of the severed ends of the plastic strips 43 are so proportioned relative to the circumference of the intervening length 11 that their ends overlap as indicated particularly in Figure 6. Under the action of the solvent (as applied to the strips 43 by the length 11, in the manner described above) and of the heat generated by the coils 35, the overlapping ends of the

severed strips 43 adhere to each other so as to form a more or less permanent continuous collar or sleeve encircling the length 11 at spaced intervals as indicated particularly in Figure 3.

The solvent also causes the plastic strips 43 to adhere, at least partially, to the surface threads of the underlying length 11 thereby providing a more secure connection of the sleeves 15 to the length 11.

The action of the heat and the solvent also tends to cause the individual threads of the open-mesh fabric to adhere to each other in the zones underlying the sleeves or collars so that there is at least a partial bonding of the open-mesh material in said zones which serves to reduce the stress on the sleeves or collars and thereby insures more secure connections.

After the male die-member 36 reaches the lowermost position shown in Figure 10, it automatically returns to the uppermost position shown in solid lines in Figure 9, under the action of its spring 40 ready for another operation.

During this cutting operation, an individual hair-net has been formed (corresponding to that portion of the length 11 extending from the die-member to the pronged holding-member 67). This hair-net is removed by the operator, and the free end of the strip 11 is then pulled tight along the line 11-a and affixed to the pronged holding-member 67, whereupon the operation is repeated.

According to the present invention, it is possible to obtain a hair-net in which the cut ends are securely and permanently held together by small, unobtrusive strips of synthetic plastic (which may be colored to correspond to the color of the hair-net so as to make them even less conspicuous) whose ends are generally permanently bonded to provide more or less continuous annular sleeves or slips and which are, at least in part, more or less permanently bonded to the synthetic plastic threads or yarn of which the hair-net is constructed.

In this way, there is provided a neat and good-looking closure which is not bulky or uncomfortable and which does not have any sharp edges or corners, such as might scratch the head or neck of the wearer.

At the same time, the bonded connection of the sleeves 15 to the synthetic plastic material of the hair-net eliminates the possibility of the sleeves or clips pulling loose.

By positioning the sleeves or clips a short distance in from the ends of the hair net, as described above, small puffs or tassels are formed which further conceal the sleeves and protect against accidental scratching of the head or neck of the wearer. The fact that the sleeves are applied under considerable pressure causes compression of the intervening portions of the hair-net as indicated schematically in Figure 6, and results in a spreading apart or expansion of the tassels 18 so as further to protect against pulling loose of the sleeves or clips. While the shear open-mesh material has been referred to hereinabove as constructed of nylon or other synthetic plastic yarn, the present invention also contemplates a hair-net constructed of cotton or other textile yarn having a surface coating of nylon or other synthetic plastic material so that the threads are capable of adhering to each other and to the fastening sleeves or clips 15 under the action of the heat and of the solvent as described above.

Accordingly, the term "synthetic plastic," as used in the appended claims with reference to

the open-mesh netted material, contemplates plastic-coated thread or yarn as well as all-plastic thread or yarn.

For the strips 43 I prefer to employ a thermoplastic material so that, under the action of the heat and pressure of the die, the overlapping ends of the strips can fuse together as described above, and, in addition, the strips can be more or less permanently molded into a circular configuration, thereby to minimize the possibility of it coming loose.

Having thus described my invention, I claim as new and desire to protect by Letters Patent:

1. In a process of the character described; the steps which comprise longitudinally stretching into a substantially tubular or rope-like strip a length of sheer open-mesh netted fabric formed at least in part by synthetic plastic threads, moistening a relatively small annular area of the stretched length with a volatile solvent for the synthetic plastic, thereafter applying two strips of synthetic plastic material to the moistened area in longitudinally-spaced tightly encircling relationship to said moistened area while said area is still wet, and thereafter drying the moistened area whereby the inner surfaces of said strips are more or less permanently adhered to at least some of the underlying synthetic plastic threads of said fabric under the dissolving action of the solvent upon said threads and said strips.

2. In a process of the character described; the steps which comprise longitudinally stretching into a substantially tubular or rope-like strip a length of sheer open-mesh netted fabric formed at least in part by synthetic plastic threads, moistening a relatively small annular area of the stretched length with a volatile solvent for the synthetic plastic, thereafter applying two strips of synthetic plastic material, in longitudinally-spaced tightly encircling relationship to said moistened area while said area is still wet, thereafter drying the moistened area whereby the inner surfaces of said strips are more or less permanently adhered to at least some of the underlying synthetic plastic threads of said fabric under the dissolving action of the solvent upon said threads and said strips, and cutting said fabric intermediate said laterally-spaced strips, thereby to form small protective tufts at the outer edges of said strips.

3. In a process of the character described; the steps which comprise longitudinally stretching into a substantially tubular or rope-like strip a length of sheer open-mesh netted fabric formed at least in part of synthetic plastic threads, moistening a relatively small annular area of the stretched length with a volatile solvent for the synthetic plastic thereafter applying two strips of thermoplastic synthetic resin to the moistened area in longitudinally-spaced tightly encircling relationship to said area while said area is still wet, with the ends of the strips in overlapping relationship, subjecting the so-applied strips to the action of heat and pressure, and thereafter drying the moistened area whereby the overlapping ends of said strips are more or less permanently fused together to form a generally continuous annulus and whereby the inner surfaces of said strips are more or less permanently adhered to at least some of the underlying synthetic plastic threads under the dissolving action of the solvent upon said threads and said strips.

4. In a process of the character described; the steps which comprise longitudinally stretching into a substantially tubular or rope-like strip a

length of sheer open-mesh netted fabric formed at least in part of synthetic plastic threads, moistening a relatively small annular area of the stretched length with a volatile solvent for the synthetic plastic thereafter applying two strips of thermoplastic synthetic resin to the moistened area in longitudinally-spaced tightly encircling relationship to said area while said area is still wet, with the ends of the strips in overlapping relationship, subjecting the so-applied strips to the action of heat and pressure, thereafter drying the moistened area whereby the over-lapping ends of said strips are more or less permanently fused together to form a generally continuous annulus and whereby the inner surfaces of said strips are more or less permanently adhered to at least some of the underlying synthetic plastic threads under the dissolving action of the solvent upon said threads and said strips, and cutting said fabric intermediate said longitudinally-spaced strips, thereby to form small protective tufts at the outer edges of said strips.

5. A hair-net consisting of the combination of a length of open-mesh nylon fabric, relatively

10
5

small fastening sleeves tightly encircling the fabric so as to provide a gathered zone near but spaced from each end of the length of fabric, each of said sleeves being a strip of plastic material permanently adhered to the nylon fabric contiguous thereto, some of the threads of the nylon fabric being permanently adhered to each other within the sleeve, the strip of plastic material being permanently adhered to itself in overlapping relation to form the sleeve, and soft tufts of spread-apart nylon fabric at each end of the length of fabric providing cushioning for the edges and surfaces of the sleeves.

HENRY F. GOLDSMITH.
